SLUG CASTING MACHINE

Frank C. Frolander, Elizabeth, N. J., assignor to
Mergenthaler Linotype Company, a corpora-
tion of New York

Application December 21, 1932, Serial No. 648,199

39 Claims. (Cl. 199—47)

This invention relates to slug casting machines, such as linotype machines of the general organization represented in United States Letters Patent No. 436,532 to O. Mergenthaler, wherein circulating matrices are released from a magazine in the order in which their characters are to appear in print, and then composed in line together with spacers, the composed line transferred to the face of a mold, the mold filled with molten metal to form a slug or linotype against the matrices which produce the type characters thereon, and the matrices and spacers thereafter returned through distributing mechanism to the magazines whence they started. More particularly, it relates to certain improvements which adapt these machines, when so desired, to cast successively and automatically a plurality of duplicate slugs from each composed line.

In the preferred embodiment illustrated (although it is not essential), the improvements have been worked out in the nature of an attachment which can be applied to almost any of the commercial machines with little or no alteration. Specifically, the equipment consists of an adjustable control member adapted to be actuated periodically from the main drive shaft of the machine, and which is connected by means of a lever to a slide mounted on the vise frame, the slide being adapted when moved to one position, first, to render a stop active which limits the upward movement of the first elevator or line transporter to prevent the removal of the composed line therefrom until the last duplicate slug has been cast from the line; secondly, to pull forward the control rod, which, through the usual intermediate connections, trips the clutch control dog to inaugurate a machine cycle of operation; thirdly, through other intermediate connections, to lock the assembler in normal position during the casting of duplicate slugs, so as to prevent the delivery to the first elevator of a second composed line until the first line has been removed thereon; and lastly, to effect the operation of a gate which causes the slugs to be delivered into one compartment or another of an improved galley which holds the duplicate slugs in separate columns. When the slide is returned to normal position upon a further actuation of the adjustable control member, the line transporter is permitted to ascend to its uppermost position after the casting of the slug, whereupon the line is transferred to the second elevator for distribution to the magazines in the customary manner, the clutch control dog again rendered operative to stop the machine at the completion of the machine cycle of opera-

tion in which the last duplicate slug is cast, and the assembler released to permit the next composed line to be delivered to the first elevator or line transporter, whereupon the operations of casting duplicate slugs are repeated.

The exact construction and mode of operation of the parts will be best understood from the detailed description to follow:

In the accompanying drawings, the invention is shown merely by way of example and in preferred form, but obviously many variations and modifications may be made therein which will still be comprised within its spirit. It is to be understood, therefore, that the invention is not limited to any specific form or embodiment, except insofar as such limitations are specified in the appended claims.

Referring to the drawings:

Fig. 1 is a front view of a portion of a linotype machine equipped with the improvements, showing the slide which operates the line transporter stop, the assembler lock, and the connections for rendering the clutch control dog inoperative in normal or inactive position, and showing also the improved galley (partly broken away) together with the gate for determining into which column of the galley the slug is to be delivered;

Fig. 2 is a plan view of a section of the machine, showing the recasting mechanism in normal or inactive position;

- Fig. 10 is a front view of a portion of the line transporter and transfer slide, showing the line transporter in the position preventing the transfer of the composed line therefrom;
- 5 Fig. 11 is a perspective view of that part of the machine, showing the clutch control elements and the mechanism for tripping the clutch control dog for inaugurating a machine cycle of operation; and
- 10 Figs. 12, 13 and 14 are rear views of a part of the machine, showing the clutch control dog in various positions of operations.
- Referring to Fig. 1, when the machine is employed in the customary manner, that is to say, to produce a single slug from each composed line, the matrices are released from their storage magazine (not shown) and the spacers from their storage magazine A by a keyboard mechanism (not shown), and are delivered to and composed 15 in line in the assembler B. The assembler B is then manually elevated to raise the composed line between the fingers c and c' of the line delivery slide C, which thereupon transfers the line from the assembler through the intermediate 20 channel D to the line transporter or first elevator E. The first elevator E then descends to carry the line to the casting mechanism where it is justified and then presented to the face of a mold unit into which molten metal is injected 25 to cast a slug against the justified line, after which the slug is trimmed and delivered to the galley R. The first elevator E ascends to its uppermost position and the line is shifted therefrom by the slide G into the upper transfer channel G', from which the spacers are returned to 30 their magazine A and the matrices raised by the second elevator (not shown) and delivered to the distributing mechanism (not shown), whereby they are restored to their proper channels 35 in the magazine whence they started.
- 40 As is well understood in the art, the various parts referred to, with the exception of the assembler B, which is under manual control, are operated from the main drive shaft M of the machine which is caused to make one complete rotation for each cycle of operation. The shaft M is driven by an electric motor through a spring actuated clutch (Figs. 11 to 14), this clutch being thrown into action by a trip dog J carried 45 by a cam J' which is fast to the main shaft. When the parts are at rest, the dog J engages and depresses a stop lever J², which, when depressed, acts through the usual connections to disengage the clutch. When, however, the dog 50 J is moved laterally to clear the stop lever J², as is done when the lever arm C² swings to the right (see Fig. 13), when the delivery slide C is released, the clutch actuating spring is allowed to engage the clutch and thus start the operation 55 of the machine.
- The trip dog J is also under manual control, there being employed for this purpose, a train of connections leading to a control lever j at the front of the machine, and which comprises in 60 part a vertical sleeve J³ mounted to turn upon a fixed rod J⁴, and which is provided near its upper end with a radially extending arm J⁵ arranged in position to engage the trip dog. This train of connections also includes a radially extending 65 arm J⁶ provided near the lower end of the sleeve J³, and which extends into the path of an upwardly extending pin J⁷ located on a rod J⁸ leading to the front of the machine, where it is connected to the control lever j by a toggle joint consisting of a link j' and a rearwardly extending arm 70 j² of the control lever j. By this arrangement, when the control lever j is swung forwardly, the sleeve J³ is manually rotated, and the arm J⁵ caused to move the trip dog J clear of the stop lever J², so that the clutch may be engaged in the manner above stated. The details of the clutch control mechanism are fully shown and described in the Rogers Patent No. 661,386, and being so well known, they do not require any further description here.
- 75 To complete the identification of the known parts which function in the operation of the recasting mechanism, it may be added that the main shaft M is also provided with a plurality of cams which rotate once during each machine cycle of operation, any one of which may be employed to control the recasting mechanism in the manner hereinafter described. In the embodiment shown, the control is effected from the drive gear M' (Fig. 2), but as stated before, it is not essential that this particular element be used, since any periodically rotating element on the machine may be used for the purpose.
- The parts so far described and their normal mode of operation in casting single slugs, in themselves constitute no part of the present invention, and are or may be of any suitable construction, such for instance as discussed in the previously mentioned Letters Patent No. 436,532, or as presented in the commercial linotype machine.
- 80 As already stated, the improved equipment is intended to adapt the machine automatically to cast duplicate slugs from each of the composed lines as desired. To this end, there are employed means which may be called into action when desired for actuation by a rotating element of the machine, such as the driving gear M', and which may be adjusted so that the first elevator E is prevented from ascending to its uppermost position, thereby preventing the transfer of the composed line therefrom, the assembler B locked against movement in normal position to prevent the delivery of a new line to the first elevator, and the clutch control dog J rendered inoperative so as to prevent the machine from stopping at the 85 end of a completed cycle of operation, thereby permitting a composed line to be returned to the casting mechanism a plurality of times, as determined by the adjustment of the control mechanism F.
- 90 All of the mechanisms necessary for the control of the elements involved in the casting of duplicate slugs are, in accordance with the invention, actuated from a single slide member S mounted in a channel bracket S' bolted on the vise frame V, and which is capable of lateral movement thereof for a limited distance, as determined by the brackets S² and S³ mounted respectively at the ends of the slide S, the slide being arrested in its rightmost position when the bracket S² abuts 95 against the inner end of the notch S⁴ in the front plate S⁶ of the channel bracket, and in its leftmost position, when the bracket S³ abuts against the inner end of the notch S⁵ in the opposite end of said front plate.
- 100 When the slide S is in its rightmost position, the elements necessary for arresting the first elevator E in a position preventing transfer of the line therefrom, for locking the assembler B to prevent delivery of a second line to the first elevator, and for rendering the clutch control dog J inoperative, are active, so that the line may again be returned to the casting mechanism during subsequent machine cycles of operation for casting duplicate slugs; whereas when the slide S is 105

in its leftmost position, such elements are inactive, so that the line may be transferred from the first elevator for distribution in the usual manner, and a new composed line delivered thereto. The manner in which these elements are operated by the slide S will be described hereinafter.

The periodically adjustable control member F is arranged to provide a large variety of adjustments, whereby the number of duplicate slugs cast from a composed line may be varied as desired, the adjustable member F being such that the slide S on the vise frame V is maintained in its active or operative position for a predetermined number of machine cycles of operation, as determined by the adjustment. The adjustable member F effects its control of the slide S through a lever L pivoted substantially at its mid-point to a bracket L' mounted on the machine frame, the lever being connected at its front end (Fig. 7) to the slide S by means of a detachable connection consisting of a retractable pin L² which normally projects upwardly between the bifurcated arms S⁷ of a connecting member S⁸ extending through a slot provided in the rear portion of the channel bracket S', and which is suitably connected to the slide S as by a screw S⁹ (see Fig. 7). The arms S⁷ slope upwardly and are divergent, as shown, in order to insure that the connecting pin L² will enter properly between the arms when the vise frame is returned to normal position after having previously been lowered. The connecting pin L² is held in normal position by a spring L³, but may be retracted from between the arms S⁷, against the tension of the spring when it is desired to use the machine without the recasting mechanism, a knob L⁴ being provided at the lower end of the pin to facilitate its retraction. To hold the pin L² in retracted position, another pin L⁵ is provided, projecting from the pin L², and which is adapted to abut against the under surface of the end of lever L, when the pin L² is withdrawn and rotated slightly.

The control member F (Figs. 2 and 4) is carried by a rear extension of the bracket L' and is provided with a plurality of cam members F' (twelve in the particular embodiment shown), which may be adjusted into and out of alinement with the rear end of the lever L. Underlying the plate F² which carries the cam members F' is a ratchet wheel F³ adapted to be engaged by a stud M² carried by the drive gear M', the arrangement being such that upon each complete rotation of the drive gear M', the control member F will be rotated through a distance equal to the pitch between two cam members. When the control member is rotated to bring an alined cam F' in operative relation with the end of the lever L, said lever will be actuated in a counterclockwise direction against the pull of a spring L⁶ anchored to the supporting bracket L', as shown in Fig. 2, to actuate the slide S on the vise frame V to the right, in which position, as hereinbefore stated, the control elements operated by the slide are rendered active to effect the recasting operations.

From the above, it will be apparent that when the cam elements F' are adjusted so that every alternate one is in alinement with the lever L, the slide S will be moved to the right during one cycle of operation, whereas during the next cycle of operation the slide S will be returned to normal position under the influence of the spring L⁶, since the position of the control element F during this cycle of operation is such that the cam F' opposite the lever L will be out of alinement therewith. Furthermore, it will be obvious that

any desired plurality of duplicate slugs may be recast simply by adjusting a proper number of cams F' in position to aline with the lever L. Thus, if it is desired to cast three duplicate slugs from one line, the control element F is adjusted so that every third cam F' is out of alinement with the lever, and the intervening cams in alinement therewith. To cast four duplicate slugs, every fourth cam is out of alinement with the lever, and for six duplicate slugs, every sixth cam, and so forth, so that with a comparatively few control elements practically any desired number of duplicate slugs may be cast automatically from a line.

As a measure of safety, the rear end of the lever L is provided with a dog L⁷, pivoted to the lever, and having an adjustable set screw L⁸ adapted to abut against an upstanding lug L⁹ on the lever, the screw being normally held against the stop by a compression spring L¹⁰ which is stronger than the spring L⁶ for returning the lever L and slide S to normal position. Under normal conditions of operation, the dog L⁷ and lever L function as a unit, but in the event of an interference preventing the actuation of the lever L or slide S, the dog L⁷ will yield against the tension of the spring L¹⁰, permitting the alined cams F' to ride past the dog without harmful results.

The construction of the adjustable control element F is shown in detail in Fig. 9. The unit is detachably mounted by means of a bolt F⁴ on the rear extension of the supporting bracket L', and as mentioned before, consists of a ratchet wheel F³ to which the cam carrying plate F² is pinned for integral rotation therewith. The cams F' are each pivoted on a stud F⁵ projecting upwardly from the plate F², and into a hollow cylindrical grip member F⁶ formed as an integral part of the cam, a spring F⁷ being provided between the head of the stud F⁵ and the base of said member, which tends to urge the cam F' toward the carrying plate. Each cam has a depending pin F⁸ adapted to be received either in a shallow recess F⁹ for holding the cam in the nonalining position or in a hole F¹⁰ extending through the plate F² for allowing the cam to come in contact with the plate in the alining or operative position. As will be observed, a recess and a hole are provided for each cam element.

As previously mentioned, the slide S mounted on the vise frame V is adapted to actuate different sets of control elements when the recasting mechanism is operated, first, means for limiting the upward movement of the first elevator E to prevent the transfer of the line therefrom; secondly, means for rendering the clutch control dog J inoperative; thirdly, means for locking the assembler B in normal position to prevent transfer of the second line to the first elevator E, and lastly, the gate R' (Fig. 6) which determines the compartment of the galley into which the slug is to be delivered.

In order to limit the upward movement of the first elevator E or line transporter, there is provided a stop V' pivoted to the vise frame V and adjacent the first elevator E (Figs. 1, 6, 7 and 8). In the normal operation of the machine, that is, when a single slug is cast from each line, the stop V' is inactive, but when it is desired to cast duplicate slugs, the stop is rotated to bring one arm V² thereof in alinement with a projecting lug E' located on the lower end of the first elevator slide E. Thus, when the stop is in active position, the first elevator E will be prevented from ascending to its uppermost position and will be

80

150

brought to rest in the position shown in solid lines in Fig. 10, wherein transfer of the line is prevented. When the first elevator E is in this position, transfer of the line is prevented by 5 means of a pin E², carried by an arm E³, mounted at the left end of the line supporting member, the pin in this position resting in front of a projecting lug G² on the end of the transfer slide G, which of course prevents the usual movement of 10 the transfer slide to the right to effect transfer of the line. When the stop V¹ is inactive, the elevator will ascend to its normal line transfer position, as shown by the dotted lines in Fig. 10, in which position the stop pin E² will come to rest 15 above the level of the projecting lug G², thus permitting the operation of the slide G in the usual manner to transfer the line.

The stop V¹ which limits the upward movement of the elevator E is actuated by the slide S, by 20 means of a pin S¹⁰, adjustably held in the bracket S², and the lower end of which extends into a notch V³ provided in a member V⁴ pivoted to a radially extending arm V⁵ of the stop V¹, when said member is turned up in its active position, 25 as shown in Figs. 6 and 7. Thus, when the slide S is moved to the right by the adjustable control member F at the rear of the machine in the manner heretofore described, the stop V¹ is caused to rotate in a counterclockwise direction, bringing 30 its operative end into alignment with the lug E' on the first elevator E to limit the upward movement thereof. When the slide S is moved to the left, the stop V¹ is rotated to inactive position, permitting the full ascent of the first elevator E, 35 and the transfer of the line therefrom in the customary manner.

When it is not desired to use the automatically recasting mechanism, the stop V¹ may be disconnected from the pin S¹⁰ merely by swinging the 40 notched connecting member V⁴ down into a horizontal position, as shown in Fig. 8, so that the stop may be manually operated, if desired, in the usual manner. In order properly to position the first elevator to prevent transfer of the line when 45 the automatic recasting mechanism is employed, a set screw E⁴ is provided in the lug E' on the lower end of the first elevator slide E which is adjustable to raise or lower the elevator in well known manner.

50 The clutch control dog J is rendered inoperative during the recasting cycles by a train of connections also actuated by the slide S and which effects the control of the dog J through the usual manual connections provided for this 55 purpose. Referring to Figs. 2 and 3, the usual bracket which carries the manual control lever j is replaced by a bracket J⁹, having a forward extension, adjacent the outer end of which is pivoted a plate J¹⁰. When the recasting mechanism is brought into action and the slide S moved to the right, this plate is swung in a counterclockwise direction to actuate the rod J⁸ forwardly through the medium of a tension spring J¹¹ attached to said rod. When this occurs, the sleeve J³ of the clutch control mechanism is rotated (as is usual when the machine is started by the manual lever j), and the arm J⁵ caused to move the trip dog J clear of the stop lever J², the clutch remaining engaged continuously as long as the slide S on the vise frame V remains in the rightmost position, or during a plurality of cycles of operation, as determined by the adjustment of the recasting control element F.

75 As shown in Figs. 1, 2, 3 and 6, the rotation

of the plate J¹⁰ is effected from the slide S through a dog S¹¹ carried by the bracket S³ at the right end of the slide. This dog has a bevelled end S¹² which contacts with a downwardly extending pin J¹² on the plate J¹⁰ to swing the latter in a counterclockwise direction to render the clutch control dog J inoperative. When the slide S is returned to normal position, during the casting of the last duplicate slug, the plate J¹⁰ is likewise returned to normal position, as determined by an upstanding pin J¹³, on the plate, abutting against the edge of the support bracket J⁹, this movement of the plate being caused by the tension of the spring J¹¹. The normal position of the plate and the associated operative parts is shown in Fig. 2. The dog S¹¹ is held in its normal operative position by a depending pin S¹³ resting against the supporting bracket S³, where it is maintained by a spring S¹⁴ pulling on the pin. If, for any reason, it is desired to lower the vise frame V on its pivots, the bevelled end S¹² of the dog S¹¹ will clear the depending pin J¹² on the pivoted plate J¹⁰. Should it happen, however, that the slide is inadvertently moved to the right when the vise frame is in its lower position, the dog may be obstructed by the depending pin J¹² when the vise is raised to normal position, but no harmful effect will result, since the dog will merely swing on its pivot against the tension of the spring S¹⁴ which holds it in place. In order to reset the mechanism, under such circumstances, it is only necessary to turn the plate J¹⁰ in a counterclockwise direction by hand, permitting the dog S¹¹ to snap back into place, after which the plate is released.

As stated before, it is desirable to prevent the delivery of a second composed line to the first elevator during the casting of duplicate slugs. In accordance with this invention, this is accomplished by locking the assembler B in normal position during those cycles of operation in which duplicate slugs are cast, means also being provided for releasing the assembler after the last duplicate slug has been cast, to permit a new line to be delivered to the elevator E. For this purpose, a dog K is adapted to be swung into and out of vertical alignment with a projecting lug B' on the assembler B. Thus, when the dog K is brought into active position overlying the lug B', which operation is brought about by the movement of the slide S on the vise frame to the rightmost position, upward movement of the assembler is prevented; whereas, when the dog is moved to inactive position, out of alignment with said lug, the assembler may be operated in the usual manner to deliver a line which has been composed therein to the first elevator E. As shown in Fig. 1, the dog K is mounted on the upper end of a rod K' carried by a bracket J¹³, 135 formed as an integral part of the bracket J⁹ carrying the manual control lever j. At its lower end, the rod has a radially extending arm K² carrying an adjustable screw K³ at its outer end, adapted to abut against the edge of the rearwardly extending arm j² of the manual control lever j. When the rod J⁸ is pulled forwardly by the operation of the slide S on the vise frame to accomplish the setting of the elements for the recasting operations, the manual lever j, 145 through its link connection j¹ with the rod J⁸, is likewise caused to swing forwardly, the arm j² of the lever j, engaging the arm K² to swing the dog K into active position in alignment with the lug B' on the assembler B. The dog K will re- 150

main in active position as long as the slide S remains in the rightmost position, and thus will prevent the operator from sending a new line to the first elevator during the casting of duplicate slugs. When the slide S is again moved to the leftmost position during the cycle of operation in which the last duplicate slug is cast, the rod J⁸ is actuated rearwardly in the usual manner by the clutch dog controlling mechanism, 5 to return the manual control lever j to normal position. The operation of the lever j in this manner, permits the dog K to be moved out of alinement with the lug B' on the assembler B by a spring K⁴ pulling on the arm K² and 10 anchored to the bracket J⁹.

If, for any reason, the spring K⁴ does not withdraw the dog to inactive position, such action is positively effected by means of an upstanding arm K⁵ connected at the front end of the space 20 band lever rock shaft G³, this arm having a spring retained dog K⁶ at its upper end adapted to coact with a pin K⁷ extending radially from the vertical shaft K', which carries the assembler lock dog K. With this arrangement, when the 25 space band lever is swung to the left during the operation of the transfer slide G after casting the last duplicate slug, the spring retained dog K⁶ will contact with the pin K⁷, and positively push the assembler lock dog out of vertical 30 alinement with the lug B' on the assembler B. In the event of an interference preventing the release of the assembler lock dog K, the dog K⁶ will yield against the tension of its retaining spring, thus preventing breakage or other harmful results to the various parts.

The improved galley R is provided with a plurality of compartments for holding the slugs in separate columns in order that duplicate slugs may be kept apart, and thus obviate the necessity of sorting them out by hand later on. In 40 the present embodiment, referring particularly to Figs. 1 and 6, the inclined galley R is divided into upper and lower compartments R² and R³, respectively, into which the slugs are selectively delivered as they are ejected from the mold, and in which they are progressively advanced by a stacking device (not shown). The means for determining the column into which the slugs are to be stacked, comprises a movable gate R' 45 positioned in line with the discharge end of the chute (not shown), into which the slugs are ejected from the mold. When the gate R' is in the lower position, as shown in Fig. 6, the ejected slug will, of course, be stacked in the upper compartment R², whereas when the gate is 50 swung upwardly, the ejected slug is stacked in the lower galley.

The gate R' is raised and lowered by the operation of the slide S on the vise frame, the means 60 for this purpose comprising an arm R⁴ pivoted to the slide channel bracket S', and which carries the gate R' at its outermost end. When the slide S is in the leftmost position, as shown in Fig. 6, the gate K' is in its lowermost position, and the slugs are delivered, as mentioned before, in the upper galley R². When, however, the slide S is moved to the rightmost position, the pivoted arm R⁴ is raised by means of an upstanding pin S¹⁵ fixedly secured in the slide S and projecting 65 upwardly through a slot S¹⁶ in the slide channel bracket S', the upper end of this pin coacting with a downwardly sloping plate R⁵ attached to and extending to the right of the pivoted arm R⁴, so that when the slide is moved to the right, 70 the pin pushes the arm to the upper position,

raising the gate and permitting the slug to be delivered to the lower galley R³. Upon the return of the slide S to the leftmost position at the beginning of the cycle, during which the last duplicate slug is cast, the gate is lowered by gravity in position to retain said slug in the upper galley. This arrangement is particularly applicable in a case where one duplicate slug only is cast, for, in such instances, the slide S is moved to the right during the casting of the first slug, and to the left during the casting of the second slug, the duplicate slugs thus being delivered into separate columns in the galley, which, of course, will obviate the necessity of sorting them out later on.

In the operation of the machine, when it is desired to cast duplicate slugs, the recasting control device F is first adjusted to cast the desired number of slugs, that is, if one duplicate slug

is to be cast, alternate cam elements F' are adjusted into position to aline with the lever L, 80 for two duplicate slugs (three similar slugs) two adjacent cam elements are adjusted in alinement and the third out of alinement, and so on. As the normal position of the machine is one 85 wherein the first elevator E may ascend to its uppermost position for transferring a line, and wherein the clutch control dog J is operative and the assembler lock K inoperative, the slide S on the vise frame V will rest in the leftmost position. Such being the case, the rear end of 90 the slide actuating lever L will be positioned opposite a cam element F' out of alinement therewith. The first composed line is then delivered to the first elevator E and the machine started in the usual manner. At the beginning of the 95

cycle of operation, and before the elevator E starts on its upward movement toward the line transfer position, the actuating stud M² on the drive gears M', rotates the control mechanism F to bring the next cam F' opposite the end of 100 the lever L, and as this element is in alinement with the lever, the latter is rocked as heretofore described to move the slide S to the right, in which position, the first elevator stop V¹, the trip J⁵ rendering the stop dog inoperative, and 105 the assembler lock K are brought into action.

At the same time, the gate R' associated with the galley R is raised. The line is justified in the usual manner, and the slug cast and delivered to the lower column R³ of the galley, but 110 the elevator is returned to normal position at the completion of the cycle without having transferred the line because of the interposition of the stop V¹. As the clutch control dog 115 is at this time inoperative, a second cycle of 120 operation is commenced. Immediately thereafter, the recasting control member F is advanced one step, bringing an unaligned cam element F' opposite the lever L, which, of course, permits the return of the lever and the slide 125 S connected thereto to the normal or leftmost position under the pull of the spring L⁶. The return of the slide S renders the first elevator stop dog V² and the assembler lock K inactive, 130 restores the clutch control mechanism to position to stop the machine at the end of the cycle, and lowers the galley gate R'. This cycle will, therefore, be the usual normal one of the machine, that is to say, the line of matrices will 135 be transferred from the first elevator for distribution, the machine stopped at the termination of the cycle, and the assembler released for transferring a second line to the elevator.

As the gate R' is in its lowermost position, the 140 slug cast during this cycle will be delivered into 145 the upper galley R². When the slide S is moved to the rightmost position, the pivoted arm R⁴ is raised by means of an upstanding pin S¹⁵ fixedly secured in the slide S and projecting 150 upwardly through a slot S¹⁶ in the slide channel bracket S', the upper end of this pin coacting with a downwardly sloping plate R⁵ attached to and extending to the right of the pivoted arm R⁴, so that when the slide is moved to the right, the pin pushes the arm to the upper position,

the upper column of the galley. As every alternate cam element F' is in alignment with the lever, the machine will continue automatically to cast one duplicate slug from each composed line transferred to the first elevator E.

When three duplicate slugs are to be cast, two successive cam elements F' will be brought into alignment with the lever L, thus rendering the various control elements active during two successive cycles of the machine, the elements being rendered inactive during the third casting cycle or when an unaligned cam is again brought opposite the end of the lever L.

The invention may readily be attached to machines already in the field, since it involves no substantial changes thereto, the installation being made simply by the attachment of the bracket L' to the main frame, the slide channel bracket S' to the vise frame, and a new bracket J⁹ substituted for the one usually employed for supporting the hand control lever.

In the accompanying drawings the invention has been shown merely in preferred form and by way of example, and obviously many variations and modifications may be made therein without departing from the spirit of the invention. It is to be understood, therefore, that the invention is not to be limited, except insofar as such limitations are specified in the appended claims.

Having thus described my invention, what I claim is:

1. In a slug casting machine, the combination of a transporter for presenting a composed line to the mold, the main drive shaft for the machine, and means actuated from said shaft for causing the transporter to present the line to the mold a plurality of times to cast a corresponding plurality of duplicate slugs, said means being adjustable to vary the number of slugs cast from each line.

2. In a slug casting machine, the combination of a transporter for presenting a composed line to the mold, an assembler wherein the line is composed, means including the delivery slide for delivering the composed line from the assembler to the transporter, means for causing the transporter to present the line to the mold a plurality of times to cast a corresponding plurality of duplicate slugs, and a lock actuated independently of the delivery slide for holding the assembler in normal position, said lock being rendered active by said last mentioned means during the casting of duplicate slugs.

3. In a slug casting machine, the combination of a transporter for presenting a composed line to the mold, an assembler wherein the line is composed, means including the delivery slide for transferring the composed line from the assembler to the transporter, the main drive shaft for the machine, means for arresting the transporter in a position to prevent transfer of the line therefrom, means for preventing delivery of a line to the transporter, and common means actuated from said drive shaft and independently of the delivery slide for rendering said transporter arresting means and said line delivery preventing means active during given cycles of operation of the machine.

4. In a slug casting machine, the combination of a transporter for presenting a composed line to the mold, an assembler wherein the line is composed, means including the delivery slide for transferring the composed line from the assembler to the transporter, the main drive shaft for

the machine, means for arresting the transporter in a position to prevent transfer of the line therefrom, means actuated independently of the delivery slide for locking the assembler in normal position, and common means actuated from the drive shaft for rendering said transporter arresting means and said assembler locking means active during given cycles of operation of the machine.

5. In a slug casting machine, the combination of a transporter for presenting a composed line to the mold, an assembler wherein the line is composed, means for delivering the composed line from the assembler to the transporter, the main drive shaft for the machine, means for arresting the transporter in a position to prevent transfer of a line therefrom, mechanism for preventing delivery of a line to the transporter, and common means actuated from the drive shaft for rendering said transporter arresting means and said line delivery preventing mechanism active during given cycles of operation of the machine and inactive during other given cycles of operation of the machine.

6. In a slug casting machine, the combination of a transporter for presenting a composed line to the mold, an assembler wherein the line is composed, means for delivering the composed line from the assembler to the transporter, the main drive shaft for the machine, means for arresting the transporter in a position to prevent transfer of a line therefrom, a lock for holding the assembler in normal position, and common means actuated from the drive shaft for rendering said transporter arresting means and said assembler lock active during given cycles of operation of the machine and inactive during other given cycles of operation of the machine.

7. In a slug casting machine, the combination of a transporter for presenting a composed line to the mold, an assembler wherein the line is composed, means for delivering the line from the assembler to the transporter, a lock for retaining the assembler in normal position, driving mechanism for the machine including a drive shaft and rotary wheel provided with a clutch controlling dog acting to stop the machine at the conclusion of a cycle of operation of the machine, and means actuated from the drive shaft to render said lock active and said dog inactive during a plurality of successive cycles of operation of the machine.

8. In a slug casting machine, the combination of a transporter for presenting a composed line to the mold, an assembler wherein the line is composed, means for delivering the line from the assembler to the transporter, means for transferring the line from the transporter, a lock for retaining the assembler in normal position, driving mechanism for the machine including a drive shaft and a rotary wheel provided with a clutch controlling dog acting to stop the machine at the conclusion of a cycle of operation of the machine, and means actuated from the drive shaft for preventing transfer of said line, for rendering said assembler lock active and said clutch dog inactive during a plurality of successive cycles of operation of the machine.

9. In a slug casting machine, the combination of casting mechanism, including a transporter for presenting a composed line to the mold, a galley for receiving the slugs and being adapted to hold them in a plurality of columns therein, and means associated with the galley and operable independently of the movement of the trans-

- porter for causing the slugs to be delivered into one or the other of said columns.
10. In a slug casting machine, the combination of a vise frame, a transporter for presenting a composed line to the mold, means for transferring the composed line from the transporter, means for preventing such transfer of the composed line until the machine has completed several cycles of operation, and automatic means including a slide mounted on the vise frame for actuating said line transfer preventing means into and out of operative position. 80
11. In a slug casting machine, the combination of a vise frame, a vertically movable transporter for presenting a composed line to the mold, and means for limiting the upward movement of the transporter after given casting operations, said means including a stop and a slide mounted on the vise frame said slide being actuated from the main drive shaft and arranged to move said stop into and out of active position. 85
12. In a slug casting machine, the combination of a vise frame, a transporter carried by the vise frame for presenting a composed line to the mold, driving mechanism including a rotary wheel provided with a clutch controlling dog, and automatic means including a slide mounted on the vise frame and actuated to operative position by a periodically operated element of the machine for preventing the action of said clutch controlling dog during given cycles of operation of the machine. 90
13. In a slug casting machine, the combination of a vise frame, a transporter carried by the vise frame for presenting a composed line to the mold, driving mechanism including a drive shaft and a rotary wheel provided with a clutch controlling dog, and means including a slide mounted on the vise frame and actuated from said drive shaft for preventing the action of said clutch controlling dog during given cycles of operation of the machine. 95
14. In a slug casting machine, the combination of a vise frame, an assembler in which a line is composed, and automatic means including a slide mounted on the vise frame and actuated to operative position by a periodically operated element of the machine for preventing the delivery of the line from the assembler during given cycles of operation of the machine. 100
15. In a slug casting machine, the combination of a vise frame, an assembler in which a line is composed, a lock for holding said assembler in normal position, and automatic means including a slide mounted on the vise frame for rendering said assembler lock active during given cycles of operation of the machine. 105
16. In a slug casting machine, the combination of an assembler in which a line is composed, a lock for holding said assembler in normal position, driving mechanism for the machine, control mechanism including a rod adapted upon actuation to render the driving mechanism active, and means actuated by the movement of the rod for rendering the assembler lock active. 110
17. In a slug casting machine, the combination of a transporter carried by the vise frame for presenting a composed line to the mold, an assembler, the main drive shaft for the machine, a lock for holding the assembler in normal position, and automatic means including a slide mounted on the vise frame and actuated from the main drive shaft for rendering said lock active during given cycles of operation of the machine. 115
18. In a slug casting machine, the combination of casting mechanism, a vise frame, an inclined galley carried thereby for receiving the slugs and being divided into upper and lower compartments for holding the slugs in separate columns, a chute for conveying the slugs to the galley, a gate pivoted on the vise frame, and a control device operating to raise the gate during given cycles of operation for delivery of the slugs to the lower galley compartment, and to lower the gate during other given cycles of operation for delivery of the slugs to the upper galley compartment. 120
19. In a slug casting machine, the combination of casting mechanism, a vise frame, an inclined galley carried thereby for receiving the slugs and being divided into upper and lower compartments for holding the slugs in separate columns, a chute for conveying the slugs to the galley, a gate pivoted on the vise frame, and automatic means operated from the main drive shaft of the machine, and including a movable slide mounted on the vise frame, for raising the gate during given cycles of operation for delivery of slugs to the lower galley compartment, and for lowering the gate during other given cycles of operation for delivery of the slugs to the upper galley compartment. 125
20. In a slug casting machine, the combination of a transporter for presenting a composed line to the mold, an assembler wherein the line is composed, means for transferring the composed line from the assembler to the transporter, the main drive shaft for the machine, a slide mounted on the vise frame and actuated from said shaft, and means operated by the slide for causing the line to be presented to the mold a plurality of times to cast a plurality of duplicate slugs. 130
21. In a slug casting machine, the combination of a transporter for presenting a composed line to the mold, a plurality of control devices adapted when active to cause the transporter to present the line to the mold a plurality of times to cast a corresponding plurality of duplicate slugs, a movable slide mounted on the vise frame for actuating said control devices and being adapted when in one position to render them active, and automatic means for operating said slide. 135
22. In a slug casting device, the combination of a transporter for presenting a composed line to the mold, a plurality of control devices adapted when active to cause the transporter to present the line to the mold a plurality of times to cast a corresponding plurality of duplicate slugs, a galley carried by the vise frame for receiving the slugs and being divided into two compartments for holding the slugs in separate columns, means associated with the galley for causing the duplicate slugs to be delivered into one or the other of said columns, a movable slide mounted on the vise frame for actuating said control devices and being adapted when in one position to render them active, said slide also controlling the means for causing the slugs to be delivered into one column or another of the galley, and automatic means for operating said slide. 140
23. In a slug casting machine, the combination of a transporter for presenting a composed line to the mold, means for preventing transfer of the line from the transporter, means normally acting to stop the machine at the conclusion of each casting cycle, means including a movable slide mounted on the vise frame for rendering said line transfer preventing means active and said stop inactive when the slide is in one position, and automatic means for operating said slide. 145
24. In a slug casting machine, the combination of a transporter for presenting a composed line to 150

- the mold, means for preventing transfer of the line from the transporter, driving mechanism for the machine including a rotary wheel provided with a clutch controlling dog acting to stop the machine at the conclusion of a cycle of operation, means including a rod for rendering said clutch controlling dog inoperative, means including a movable slide mounted on the vise frame for rendering said line transfer preventing means and 5 said rod active when said slide is in one position, and automatic means for operating said slide.
25. In a slug casting machine, the combination of a transporter for presenting a composed line to the mold, means for preventing transfer of the line from the transporter, means for preventing delivery of a second line to the transporter, means including a movable slide mounted on the vise frame for rendering said line transfer preventing means and said line delivery preventing means 10 active when said slide is in one position, and automatic means for operating said slide.
26. In a slug casting machine, the combination of casting mechanism, an assembler in which a line is composed, means for delivering the composed line from the assembler to the casting mechanism, a lock for holding the assembler in normal position, driving mechanism for the machine including a rotary wheel provided with a clutch controlling dog acting to stop the machine 15 at the conclusion of a cycle of operation, means including a movable slide mounted on the vise frame for rendering said assembler lock active and said clutch controlling dog inactive when the slide is in one position, and automatic means for 20 operating said slide.
27. In a slug casting machine, the combination of a transporter for presenting a composed line to the mold, means for preventing transfer of the line from the transporter, means for preventing delivery of a second line to the transporter, driving mechanism for the machine including a rotary wheel provided with a clutch controlling dog acting to stop the machine at the conclusion of the cycle of operation, means for 25 preventing the operation of said clutch controlling dog, means including a movable slide mounted on the vise frame and being adapted when in one position to render operative said line transfer preventing means, said line delivery preventing means, and said means preventing operation 30 of the clutch controlling dog, and automatic means for operating said slide.
28. In a slug casting machine, the combination of a line transporter for presenting a composed line to the mold, driving mechanism for the machine including a rotary wheel provided with a clutch controlling dog acting to stop the machine at the conclusion of a cycle of operation, a galley for receiving the slugs and being divided into two 35 compartments for holding the slugs in separate columns, a plurality of control devices including means for preventing transfer of the line from the transporter, means for preventing delivery of a second line to the transporter, and means for preventing the operation of the clutch controlling dog, means for causing the slugs to be delivered into one or the other columns of the galley, means including a movable slide mounted 40 on the vise frame and being adapted when the slide is in one position to render said controlling devices active and for causing slugs to be delivered into one column of the galley and when in another position to permit said controlling devices to be inactive and to cause the slugs to be 45 delivered to the other column of the galley, and automatic means operating said slide.
29. In a slug casting machine, the combination of a line transporter for presenting a composed line to the mold, a plurality of control devices adapted when active to cause the transporter to present the line to the mold a plurality of times to cast a corresponding plurality of duplicate slugs, a movable slide mounted on the vise frame and operatively connected with said control devices and being adapted when in one position, concurrently to render said control devices active, and automatic means operating said slide.
30. In a slug casting machine, the combination of driving mechanism, a train of connections for controlling the driving mechanism including a rod, a vise frame pivotally mounted on the machine and adapted to be swung from an operative to an inoperative position, means comprising a member mounted on the vise frame for operating a plurality of control devices for causing the machine to operate automatically for a plurality of successive cycles to cast duplicate slugs and including a connection with the said rod, operating means for said member on the vise frame, and a connection between said member and its operating means, both said connections being so arranged and constructed that they are automatically broken when the vise frame is moved from 105 operative to inoperative position.
31. In a slug casting machine, the combination of a transporter for presenting a composed line to the mold, an assembler wherein the line is composed, means for delivering the composed line 110 from the assembler to the transporter, means for causing the transporter to present the line to the mold a plurality of times to cast a corresponding plurality of duplicate slugs, a lock for holding the assembler in normal position, and a slidable member mounted on the vise frame of the machine and constituting a common member through which the control of the transporter is effected and through which the assembler lock is rendered 115 operative during the casting of duplicate slugs.
32. In a slug casting machine, the combination of a transporter for presenting a composed line to the mold, an assembler wherein the line is composed, means for transferring the composed line from the assembler to the transporter, the main drive shaft for the machine, means for arresting the transporter in a position to prevent transfer of the line therefrom, means for preventing delivery of a line to the transporter, and a common slidable member mounted on the vise 120 frame and actuated from the drive shaft for rendering said transporter arresting means and said line delivery preventing means active during given cycles of operation of the machine.
33. In a slug casting machine, the combination of a transporter for presenting a composed line to the mold, an assembler wherein the line is composed, means for transferring the composed line from the assembler to the transporter, the main drive shaft for the machine, means for 125 arresting the transporter in a position to prevent transfer of the line therefrom, means for preventing delivery of a line to the transporter, and a common slidable member mounted on the vise frame and actuated from the drive shaft for rendering said transporter arresting means and said line delivery preventing means active during given cycles of operation of the machine and inactive during other given cycles of operation of the machine.
